(57) **ABSTRACT**

A variable pitch fan blade mechanism, particularly well suited for automotive applications, wherein the blade pitch is compliantly responsive to selective actuation of a linear actuator. A linear actuator is disposed in the fan shaft composed of an electric drive component drivingly engaged with a follower component, a set of fan blades resiliently attached to a head of the follower component, and a push assembly connected to the fan shaft composed of a push plate and a plurality of push rods, one push rod for each fan blade. Each push rod engages its respective fan blade adjacent an edge thereof. The fan blades are resiliently biased toward the push rods such that axial movement of the push rods in response to actuation of the linear actuator results in compliant changes of pitch of the blades.

**FAN BLADES HAVING VARIABLE PITCH
COMPLIANTLY RESPONSIVE TO A LINEAR
ACTUATOR**

TECHNICAL FIELD

The present invention relates to fans, and more particularly to variable pitch fan blades. Still more particularly, the present invention relates to variable pitch fan blades in which the blade pitch is compliantly responsive to selective actuation of a linear actuator.

BACKGROUND OF THE INVENTION

In automotive applications, the motor vehicle includes one or more cooling fans and one or more heat exchangers (i.e., one each for the engine cooling system, the transmission, the air conditioning, and electrical components) which are mounted to the front of the motor vehicle, wherein the one or more fans provides a stream of forced air through the fins of the one or more heat exchangers.

As shown by way of example at FIG. 1, a fan assembly 10 includes two fans 12, 14, each having fixed pitch blades 16. The fans 12, 14 are typically driven mechanically by the engine, either by the crankshaft or by a belt-driven accessory pulley spinning at engine speed, wherein electro-viscous clutch mechanisms are commonly employed to selectively disable the fan (these clutch mechanisms can incur viscous friction and energy loss to heat), or alternatively each fan is powered electrically, wherein the electric motor rotational speed may be either preset or variable.

Under various driving conditions, more or less fan forced air flow is necessary. For example, a large amount of fan forced air is required, as for example on hot days when the motor vehicle is running but stopped or is traveling slowly, towing or traveling on an upgrade. On the other hand, little or no fan forced air is necessary on cold days when the motor vehicle is traveling at high speed. Most driving conditions are between these two extremes, wherein it would be desirable for the fan forced air to adjust to the driving conditions so as to always provide an optimal air flow with the least amount of energy consumption to drive the one or more fans.

Variable pitch blades are known for fixed wing aircraft propellers and helicopter rotors. However, these applications involve complex and necessarily robust mechanisms that are unsuitable for fans of the type presently being considered, where minimization or elimination in parasitic loss is an important consideration.

What remains needed in the art is a simple and lightweight mechanism for adjusting fan pitch, which is particularly suited to automotive application.

SUMMARY OF THE INVENTION

The present invention is a variable pitch fan blade mechanism, particularly well suited for automotive applications, wherein the blade pitch is compliantly responsive to selective actuation of a linear actuator such that parasitic energy loss is minimized or eliminated.

The variable pitch fan blade mechanism according to the present invention includes a fan shaft; a linear actuator disposed in the fan shaft, being composed of an electric drive component drivingly engaged with respect to a follower component; a set of fan blades resiliently attached to a head of the follower component; and a push assembly connected to the fan shaft composed of a push plate and a plurality of push rods, one push rod, respectively, for each fan blade. Each push

2

rod engages its respective fan blade adjacent an edge thereof. The fan blades are resiliently biased toward the push rods such that axial movement of the push rods results in compliant changes of pitch of the blades.

5 A preferred electric drive component is an electric motor having a threaded motor shaft which threadingly engages a threaded bore of the follower component, wherein the follower component is axially splined with respect to the fan shaft. Electricity from an external source is delivered to the electric drive component, as for example by a ring and brush contact arrangement disposed on the fan shaft.

In operation, the fan shaft is rotatably driven by any conventional modality, such as a belt or direct drive with respect to an external engine or motor. Selective actuation of the 15 electric motor results in threading of the threaded motor shaft with respect to the threaded bore, wherein, depending upon the direction of rotation of the threaded motor shaft, the follower axially moves toward or away from the electric motor, slidably on the splines. As a consequence of this axial 20 movement of the follower component, the push rods cause either more or less resilient tilting of the blades so as to thereby compliantly change the blade pitch.

Accordingly, it is an object of the present invention to provide a variable pitch fan blade mechanism, particularly well suited for automotive applications, wherein the blade pitch is compliantly responsive to selective actuation of a linear actuator such that parasitic energy loss is minimized or eliminated.

This and additional objects, features and advantages of the 30 present invention will become clearer from the following specification of a preferred embodiment.

BRIEF DESCRIPTION OF THE DRAWINGS

35 FIG. 1 is a perspective view of a prior art fan assembly of the type used for automotive applications.

FIG. 2 is a perspective view of a variable pitch fan blade mechanism according to the present invention.

FIG. 3 is a partly sectional side view of the variable pitch 40 fan blade mechanism according to the present invention, wherein the fan blades have a neutral pitch.

FIG. 3A is a partly sectional side view of a fan blade and its 45 respective push rod, seen along line 3A-3A of FIG. 3.

FIG. 4 is a partly sectional side view of the variable pitch 50 fan blade mechanism according to the present invention, wherein the fan blades have a positive pitch.

FIG. 4A is a partly sectional side view of a fan blade and its 55 respective push rod, seen along line 4A-4A of FIG. 4.

FIG. 5 is a partly sectional side view of the variable pitch fan blade mechanism according to the present invention, wherein the fan blades have a negative pitch.

FIG. 5A is a partly sectional side view of a fan blade and its 60 respective push rod, seen along line 5A-5A of FIG. 5.

FIG. 6 is a perspective view of a fan assembly of the type 65 used for automotive applications, wherein a pair of fans are equipped with the variable pitch fan blade mechanism according to the present invention.

DESCRIPTION OF THE PREFERRED
EMBODIMENT

Referring now to the Drawing, FIGS. 2 through 6 depict a preferred embodiment of the variable pitch fan blade mechanism 100 according to the present invention.

65 With initial reference to FIGS. 2 through 3A, the variable pitch fan blade mechanism 100 includes a fan shaft 102 which is connected distally (not shown) to a conventional bearing

and is driven conventionally, as discussed hereinabove. A proximal end portion **102p** of the fan shaft **102** is configured to provide an axially aligned motor receptacle **104** and a communicating follower receptacle **106** having a sidewall **108** provided with a plurality of axially aligned splines **110**. A drive component **112**, composed, by way of example, of an electric motor **114** having a threaded motor shaft **116**, is seated in the motor receptacle **104**, wherein the electric motor is prevented from rotating in the motor receptacle, as for example by a non-circular mutual engagement or by a key-slot interference **118**. The electric motor **114** may be preferably a stepper motor having conventional circuitry associated therewith which remembers the absolute rotational position of the threaded motor shaft **116**. Wiring **120** from the electric motor **114** exits the fan shaft **102** in the form of external rings **122** which are affixed to the fan shaft. Conventional brush contacts **122b** slide on the slip ring to thereby electrically connect the electric motor to a conventional external electric power circuit (not shown).

The drive component **112** is drivingly engaged with respect to a follower component **130**. The follower component **130** includes a pedestal **132** having axially aligned splines **134** on its periphery. The follower component **130** further has an axially aligned threaded bore **136**. The pedestal **132** is received in the follower receptacle **106**, wherein the two sets of splines **110**, **134** mutually mesh, allowing mutual axial sliding without rotation as the threaded motor shaft **116** is threadingly engaged with respect to the threaded bore **136**. In this regard, actuation of the electric motor **114** in one direction results in the follower component **130** moving axially away from the electric motor, while rotation of the electric motor in the opposite direction results in the follower component moving toward the electric motor.

The follower component **130** further includes a head **138**. A plurality of fan blades **140** are resiliently attached to the head **138**. The preferred attachment is via a torsion bar **142** non-rotatingly anchored at one end in radial or, more preferably, tangential (as shown), disposition of the head **138** and non-rotatingly anchored at the other end in, preferably, bisecting disposition to an inside end **140i** of its respective fan blade **140** so that a torque moment is established between the torsion bar and the push rod. The torsion bars **142** each have a pre-loaded torsional bias, as will be described momentarily.

The drive component **112** in combination with the follower component **130** provide, collectively, a linear actuator **148**.

A push assembly **150** is connected to the proximal end **102e** of the fan shaft **102** (i.e., at the end of the proximal end portion **102p**), being composed of a push plate **152** and a plurality of upstanding (axially aligned) push rods **154**, there being one push rod, respectively, for each fan blade **140**. Each push rod **154** engages its respective fan blade adjacent a contact edge **140e** thereof, all engaging at either the leading edge **140el** or following edge **140ef**. The aforementioned torsional biasing TB of the torsion bars **142** (see FIG. 3A) is such that the contact edge **140e** of each fan blade is resiliently biased into abutment with the rod end **154e** of its respective push rod such that axial movement of the push rods (via the above described linear actuator **148**) results in resiliently compliant changes of pitch of the blades.

With particular reference to FIGS. 3 through 5A, operation of the variable pitch fan blade mechanism **100** will now be detailed.

It is seen in FIGS. 3 and 3A, merely by exemplary reference, that the linear actuator **148** has provided a neutral pitch to the fan blades **140**, wherein by "neutral pitch" is meant that the fan blades have a blade pitch BP which is oriented parallel to the plane of rotation P (which is, itself, axially normal to the

fan shaft axis SA) whereby rotation of the fan shaft results in no axial forced air movement. At this orientation, the center of each of the torsion bars **142** is spaced a distance **X₁** from the push plate **152**.

- 5 Referring next to FIGS. 4 and 4A, the electric motor **114** has been actuated, whereby the threaded motor shaft **116** has threaded in the threaded bore **136** so as to thereby move the follower component **130** with respect to the push plate **152** from the position shown at FIG. 3 to that shown at FIG. 4.
- 10 Electric power to the electric motor **114** through the rings **122** is only provided during the time the threaded motor shaft threads in the threaded bore. As a consequence of this axial movement of the follower component (and its push plate), the push rods have caused increased resilient tilting of the fan blades as compared to that of FIG. 3 so as to thereby compliantly change the blade pitch.

15 In this regard, the linear actuator **148** has been actuated so as to cause the push rods **154** to impart a positive pitch to the fan blades, wherein by "positive pitch" is meant that the blade pitch is acutely angled with respect to the plane of rotation P and direction of rotation (see arrow DR), whereby rotation of the fan shaft results in forced air movement axially toward the distal end of the fan shaft (see arrow FA). At this orientation, the center of each of the torsion bars **142** is spaced a distance **X₂** from the push plate **152**. This movement of the push plate relative to the fan blades causes an increase in the torsional biasing of the torsion bars.

20 Referring next to FIGS. 5 and 5A, the electric motor **114** has been actuated, whereby the threaded motor shaft **116** has threaded in the threaded bore **136** (in the opposite rotational direction for that used to go from FIG. 3 to FIG. 4 as recounted immediately above) so as to thereby move the follower component **130** with respect to the push plate from the position shown at FIG. 3 to that shown at FIG. 5. Again, electric power to the electric motor through the rings **122** is only provided during the time the threaded motor shaft threads in the threaded bore. As a consequence of this axial movement of the follower component (and its push plate), the push rods cause decreased resilient tilting of the fan blades as compared to that of FIG. 3 so as to thereby compliantly change the blade pitch.

25 In this regard, the linear actuator **148** has been actuated so as to cause the push rods **154** to impart a negative pitch to the fan blades, wherein by "negative pitch" is meant that the blade pitch is acutely angled with respect to the plane of rotation P and direction of rotation (see arrow DR), whereby rotation of the fan shaft results in forced air movement axially away from the distal end of the fan shaft (see arrow FA'). At this orientation, the center of each of the torsion bars **142** is spaced a distance **X₃** from the push plate **152**. This movement of the push plate relative to the fan blades causes a decrease in the resilient torsional biasing of the torsion bars, yet the torsional biasing is still strongly biasing the fan blade edge toward the always abutting push rod end.

30 From the foregoing description, it is clear that the fan blades may be made to compliantly change blade pitch to any amount of increasing/decreasing positive pitch and/or increasing/decreasing negative pitch, and that electric power is only needed during pitch change (and this is the case whether the fan shaft rotates clockwise or counter-clockwise).

35 FIG. 6 depicts an automotive application of the variable pitch fan blade mechanism **100**, implemented as a fan assembly **200** analogous to that shown at FIG. 1. In an automotive application, the variable pitch fan blade mechanism **100** according to the present invention increases fuel economy by eliminating the losses inherent in variable speed electric fans

5

or in viscous-clutch engine driven fans, and by allowing for decreased fan work at high vehicle speeds when air flows are inherently higher. Fan work can essentially be adjusted to the powertrain cooling needs, thus optimizing fan work and preventing parasitic energy loss.

To those skilled in the art to which this invention appertains, the above described preferred embodiment may be subject to change or modification. Such change or modification can be carried out without departing from the scope of the invention, which is intended to be limited only by the scope of the appended claims.

The invention claimed is:

1. A variable pitch fan blade mechanism, comprising:
a fan shaft having a proximal end portion;
a linear actuator connected with said fan shaft at said proximal end thereof, said linear actuator comprising a drive component seated in said fan shaft and a follower component slidably movable axially with respect to said fan shaft responsive to actuation of said linear actuator;
a plurality of push rods connected to said fan shaft; and
a plurality of fan blades connected to said follower component, each push rod abutting a respective fan blade, wherein each fan blade is resiliently biased toward its respective push rod;
wherein actuation of said linear actuator results in said follower component moving in relation to said fan shaft such that each said fan blade moves in relation to its respective push rod such that a blade pitch of each said fan blade is compliantly changed with respect to a blade rotation plane.

2. The variable pitch fan blade mechanism of claim 1, wherein:

- said drive component further comprises:
a motor receptacle formed in said proximal end portion of said fan shaft;
an electric motor non-rotatably seated in said motor receptacle, said electric motor having a threaded motor shaft; and
a follower receptacle formed in said fan shaft in communicating relation to said motor receptacle, said follower receptacle having a splined sidewall; and
said follower component further comprises:
a splined pedestal meshed with said splined sidewall so that said pedestal is non-rotatably slidably axially with respect to said fan shaft, said pedestal having a threaded bore into which said threaded motor shaft is threaded, wherein actuation of said motor causes said follower to axially slide in said follower receptacle; and
a head connected to said pedestal, wherein said fan blades are connected to said head.

3. The variable pitch fan blade mechanism of claim 2, further comprising:

- a push plate connected to said proximal end portion of said fan shaft, wherein said push rods are connected to said push plate in upstanding relation thereto.

4. The variable pitch fan blade mechanism of claim 2, further comprising:

- a plurality of torsion bars, each torsion bar connecting an inside end of a respective fan blade to said head, wherein each torsion bar has a torsional bias which resiliently biases its respective fan blade abuttingly toward its respective push rod; and
wherein each push rod abuts its respective fan blade adjacent an edge thereof so as to establish a torque moment with respect to the push rod.

6

5. The variable pitch fan blade mechanism of claim 4, further comprising:

- a push plate connected to said proximal end portion of said fan shaft, wherein said push rods are connected to said push plate in upstanding relation thereto.

6. The variable pitch fan blade mechanism of claim 4, wherein each said torsion bar is connected to said head in tangential relation thereto.

7. The variable pitch fan blade mechanism of claim 6, further comprising:

- a push plate connected to said proximal end portion of said fan shaft, wherein said push rods are connected to said push plate in upstanding relation thereto.

8. A fan assembly comprising at least one fan, wherein each fan comprises:

- a fan shaft having a proximal end portion;
a plurality of fan blades rotatively driven by said fan shaft; and

- a variable pitch fan blade mechanism, comprising:
a linear actuator connected with said fan shaft at said proximal end thereof, said linear actuator comprising a drive component seated in said fan shaft and a follower component slidably movable axially with respect to said fan shaft responsive to actuation of said linear actuator; and

- a plurality of push rods connected to said fan shaft, wherein said plurality of fan blades are connected to said follower component, each push rod abutting a respective fan blade, wherein each fan blade is resiliently biased toward its respective push rod;

- wherein actuation of said linear actuator results in said follower component moving in relation to said fan shaft such that each said fan blade moves in relation to its respective push rod such that a blade pitch of each said fan blade is compliantly changed with respect to a blade rotation plane.

9. The fan assembly of claim 8, wherein:

- said drive component further comprises:
a motor receptacle formed in said proximal end portion of said fan shaft;

- an electric motor non-rotatably seated in said motor receptacle, said electric motor having a threaded motor shaft; and

- a follower receptacle formed in said fan shaft in communicating relation to said motor receptacle, said follower receptacle having a splined sidewall; and

said follower component further comprises:

- a splined pedestal meshed with said splined sidewall so that said pedestal is non-rotatably slidably axially with respect to said fan shaft, said pedestal having a threaded bore into which said threaded motor shaft is threaded, wherein actuation of said motor causes said follower to axially slide in said follower receptacle; and

- a head connected to said pedestal, wherein said fan blades are connected to said head.

10. The fan assembly of claim 9, further comprising:

- a push plate connected to said proximal end portion of said fan shaft, wherein said push rods are connected to said push plate in upstanding relation thereto.

11. The fan assembly of claim 9, further comprising:

- a plurality of torsion bars, each torsion bar connecting an inside end of a respective fan blade to said head, wherein

each torsion bar has a torsional bias which resiliently biases its respective fan blade abuttingly toward its respective push rod; and

wherein each push rod abuts its respective fan blade adjacent an edge thereof so as to establish a torque moment with respect to the push rod.

12. The fan assembly of claim 11, further comprising:

a push plate connected to said proximal end portion of said fan shaft, wherein said push rods are connected to said push plate in upstanding relation thereto.

13. The fan assembly of claim 11, wherein each said torsion bar is connected to said head in tangential relation thereto.

14. The fan assembly of claim 13, further comprising: a push plate connected to said proximal end portion of said fan shaft, wherein said push rods are connected to said push plate in upstanding relation thereto.

* * * * *
